UNITED STATES PATENT OFFICE.

JOSEPH J. SCHOLFIELD, OF PROVIDENCE, RHODE ISLAND.

CLOTH WINDING AND MEASURING MACHINE.

No. 813,743.

Specification of Letters Patent.

Patented Feb. 27, 1906.

Application filed July 6, 1903. Serial No. 164,440.

To all whom it may concern:

Be it known that I, JOSEPH J. SCHOLFIELD, a citizen of the United States, residing at Providence, in the State of Rhode Island, 5 have invented a new and useful Improvement in Cloth Winding and Measuring Machines, of which the following is a specification.

My invention relates to a machine for winding webs of cloth in pieces of definite length into tightly-wound cylindrical package-rolls; and it consists in improved means for winding the web into a package-roll and in improved means for cutting off the proper 15 length of web to form the package-roll and for holding the forward end of the web at its cut position, as hereinafter set forth.

In the accompanying drawings, Figure 1 represents an elevation of the delivering side 20 of the machine. Fig. 2 represents a top view. Fig. 3 represents an end view. Fig. 4 represents a side view of the winding-mandrel when the parts of the mandrel are closed upon each other. Fig. 5 represents the same 25 when the parts of the mandrel are separated. Fig. 6 represents an enlarged detail section taken in the line 6 6 of Fig. 3, showing the means for rotating one portion of the mandrel. Fig. 7 represents an enlarged side 30 view of the carriage for the rotary cutter which serves to sever the web at the proper length, taken from the line 7 7 of Fig. 9. Fig. 8 represents an enlarged section taken in the line 8 8 of Fig. 9, showing a detail view of a 35 portion of the mechanism for stopping the machine when the proper quantity of cloth has been measured. Fig. 9 represents an enlarged section taken in the line 9 9 of Fig. 2. Fig. 10 represents a detail section taken in 40 the line 10 10 of Fig. 9. Fig. 11 represents an enlarged section taken in the line 11 11 of Fig. 10.

In the drawings, A represents the frame of the machine. B is the measuring-roll, over 45 which the web of the cloth C is drawn, and D is the presser-roll for holding the web C against the measuring-roll. Upon the outer end of the shaft E of the measuring-roll B is secured the worm F, engaging with the teeth 50 of the worm-gear G, which is in mesh with the teeth of the pinion G', held upon the sleeve H, which latter at its lower end is provided with the notched disk I and at its up-

per end with the dial-plate J, the said sleeve being held to revolve upon the fixed stud K, 55 at the upper end of which is secured the pointer L.

The winding-mandrel M is formed of the two parts N and O, the part N consisting of the spring-arms a a, connected to a head b, 60 which is jointed at k to the forward end of the rotary spindle P, as shown in Fig. 6, the other part O of the mandrel M being provided with the head c and the squared shank d, which loosely enters the squared end opening of the longitudinally-movable spindle Q, 65 held in the rotary sleeve R and actuated longitudinally by means of the screw S and hand-wheel T. The said spindles P and Q are rotated in unison with each other by 70 means of the gear U upon the sleeve R and the gear U' upon the spindle P, the gears V V upon the driving-shaft W, and the intermediate gears X X. The frictionally-driven pressing-rolls Y Y Y, which surround the 75 winding-mandrel M, are journaled in radial slots Z, formed in the stationary disks A' A' at opposite ends of the machine. The journals e e e of the pressing-rolls Y Y Y pass through the cam-slots f f f of the cam-disks 80 B' B', which are supported loosely upon the rotary spindle P and the movable spindle Q and connected with each other by means of the bar C', made of sufficient weight to cause the rolls Y Y Y to be drawn inward to the 85 mandrel M, with the proper degree of pressure to cause the winding of the package-roll with the required degree of tightness, and when the mandrel M is made of comparatively 90 short length the revolution of the longitudinally-movable spindle Q may be dispensed with, the shank d of the mandrel being in this case made cylindrical and adapted to revolve in a corresponding cylindrical opening in the end of the spindle.

The automatically-disengaging shipper-lever D' is pivoted to the frame A at the point E' and actuated for disengagement by means of the spring F' upon the clutch-rod L', to which the shipper-lever D' is connected. The 100 shipper-lever is held and guided at its upper end by means of the bracket H', provided with the hub g, in which is held the spring-actuated catch-bolt H², which serves to retain the shipper D' in its set position, as shown in 105 Fig. 8, the said catch-bolt H² being limited in

its forward movement by means of the pin m of the bolt, which pin is held in the slot n of the hub g . The disengaging-lever I' is pivoted at the stud J' , Fig. 9, and provided at its 5 end with the beveled surface h , adapted by its cam action upon the edge of the shipper-lever D' to cause its disengagement from the spring-actuated catch-bolt H^2 to stop the machine, the required movement of the disengaging-lever I' being effected by means of the 10 spring K' and sliding bolt K^2 , the action of which causes the end i of the lever I' to enter the notch j in the edge of the disk I , thus allowing the required movement of the lever I' 15 for effecting the disengagement of the shipper-lever whenever the proper quantity of cloth has been wound upon the mandrel M , this quantity being determined by the relative diameters of the gear G and pinion G' , 20 by means of which the notched disk I is rotated. Upon the parallel guide-rods $M' M'$ is placed the sliding hand-operated carriage N' for the rotary cutter O' , which is held upon a short shaft P' , arranged to turn upon the center pointed screws $k k$, and upon the shaft P' 25 is secured the scored pulley Q' , (shown in Fig. 9,) and above the pulley Q' in the sliding carriage N' are placed the loose idler-pulleys $R' R'$, the said pulley Q' and cutter O' being 30 rotated in opposite directions by means of the cord S' as the carriage N' is moved back and forth along the guide-rods $M' M'$, the ends $l l$ of the said cord S' being firmly attached to the standards $T' T'$ and passing over the 35 idler-pulleys $R' R'$ and under the pulley Q' . To the upright standards $T' T'$ is secured the cutting-bed A^2 , having at the forward portion of its upper surface the cutting-bar B^2 , along the rear edge of which the rotary cutter O' 40 moves, and back of the rotary cutter O' upon the bed A^2 is placed the strip of card-clothing C^2 , which serves to prevent the backward movement of the severed end of the web, and thus retaining the end at all times in 45 proper position for being pulled forward by the attendant of the machine for again threading up the mandrel, the web C being pressed down onto the teeth of the card-clothing by means of the presser D^2 upon the carriage N' , and when the cut-off portion of the 50 web has been fully wound upon the mandrel M then upon opening the cluster of pressing-rolls $Y Y Y$ by means of the cam-disks $B' B'$ and withdrawing the spindle Q by means of 55 the screw S the mandrel M and cloth package M^2 , rolled thereon, may be turned outward upon the joint k and the rolled package drawn therefrom upon the prior withdrawal of the loose part O of the mandrel. 60 The web C , which is to be wound into a package-roll, passes, as shown by the broken line, Fig. 9, over the shaft Y' , thence over the guide-rod V' , thence around the tension-bars $W' W'$,

which are made adjustable by means of the gear o , secured to one of the said bars and the 65 pawl p , pivoted to the frame A , the said bars being held parallel with each other by means of suitable connecting-arms, thence under the guide-rod X' , and over the measuring-roll B and under the presser-roll D , thence over the 70 cutting-bed A^2 and over the guide-rod Z' to the winding-mandrel M , and when the machine is started into operation by the movement of the shipper D' to its set position, as shown in Fig. 8, and the notched disk I has made one 75 complete revolution, thus measuring off the proper quantity of cloth for the package-roll, the end i of the lever I' will enter the notch j at the edge of the disk and cause the stopping of the machine, whereupon the cutter-carriage N' is to be moved from side to side of the machine to sever the web, and then upon the completion of the winding the package-roll may be removed from the mandrel, as before described. 80 85

I claim as my invention—

1. In a cloth-winding machine, the combination of the rotary spindle, the head jointed to the forward end of the rotary spindle, and the yielding arms connected to the said head, 90 the said head and yielding arms forming the outer portion of a winding-mandrel, with a longitudinally-movable spindle and an inner mandrel portion having a head which engages with the end of the longitudinally-mov- 95 able spindle, substantially as described.

2. In a cloth-winding machine, the combination of the revolving spindle, the winding-mandrel made in two parts, one of which is jointed to the revolving spindle, with the series of pressure-rolls, and means for imparting simultaneous movement thereto, toward or from the mandrel, substantially as de- 100 scribed.

3. In a cloth-winding machine, the combination of the winding-mandrel and the series of pressure-rolls, with the stationary slotted disks in which the pressure-rolls are journaled, and the connected cam-disks, by means of which the pressure-rolls are adjusted, sub- 110 stantially as described.

4. In a cloth winding and measuring machine, the combination of the winding-mandrel, the series of pressure-rolls adapted for movement toward and from the mandrel, 115 with the measuring-roll, the notched disk operatively connected with the shaft of the measuring-roll, the spring-actuated disengaging-lever adapted for engagement with the notched disk, the spring-actuated catch-bolt, and the spring-actuated shipper-lever released by the movement of the disengaging-lever, substantially as described. 120

5. In a cloth winding and measuring machine, the combination of the winding-mandrel, the measuring-roll, the notched disk op- 125

eratively connected with the shaft of the measuring-roll, the spring-actuated disengaging-lever adapted for engagement with the notched disk, the spring-actuated catch-
5 bolt and the spring-actuated shipper-lever released by the movement of the disengaging-lever, with the rotary cutter, and means for

holding the forward end of the severed web, substantially as described.
